UNITED STATES PATENT OFFICE.

JAMES E. KIPFER, OF COLORADO SPRINGS, COLORADO.

SHOE-DRESSING APPARATUS.

Application filed June 7, 1921. Serial No. 475,593.

To all whom it may concern:

Be it known that I, JAMES E. KIPFER, a citizen of the United States, residing at 706 South Nevada Avenue, in the city of Colorado Springs, in the county of El Paso and State of Colorado, have invented a new and useful Shoe-Dressing Apparatus, of which the following is a specification.

My invention relates to improvements in 10 Shoe-Dressing Apparatus installed in a shoe-store having a shoe-repair department, and in which a depressed floor for the shoe-dressing operator allows the customer whose shoes are to be dressed while on the feet, to 15 take a seat on the level floor of the store without climbing up to the seat, or mounting any above the floor, or raising the feet above the floor on which he is walking; and the objects of my improvement are, first, 20 to provide a more nearly perfect means of dressing shoes; second, to provide a more rapid means of dressing shoes; third, to provide means for dressing the shoes of a customer without hurting or heating the customers feet in the process; fourth, to provide 25 a cooling air-bath to the shoes and feet of the customer; fifth, to save the time of the customer and operator; and sixth, to preserve the grain of the leather in the shoes 30 dressed and for many other objects.

I obtain these objects by means of the mechanism illustrated in the accompanying drawings, in which—

Figure 1, is a plan view of a retail shoe-store and embodying a preferred form of this invention; Fig. 2, is a sectional elevation of a portion of this invention, and illustrating a chair, a railing and curtain, a foot and footrest, and a portion of a pit; Fig. 3, 35 is a sectional plan of a portion of the pit illustrating the relative positions of parts; Fig. 4 is a sectional elevation of the rotatable stand on the arms of which the electric motors are suspended; Fig. 5, is a sectional 40 elevation showing the motor suspended on a rail under the floor; Fig. 6, is a front broken elevation of Fig. 5; A, indicates the usual position of the operator; B, indicates the interior of a store-room; C, indicates the pit 45 in which the mechanical equipment is installed. My invention comprehends a circular pit as shown in Fig. 1 and a rectangular pit as shown in Fig. 6.

In the rectangular pit the motor is shown

suspended under the floor in Fig. 5, and in 55 the circular pit it may be supported as in Figs. 1 and 3 on a rotatable standard.

Referring to Figure 1, the numerals 1 indicate chairs mounted upon rails 2. Similar numerals and letters refer to similar parts 60 throughout the several views of the drawings and in the specification.

In the service described in this invention, the customer takes a seat in a common chair on the level floor, and when the chair 1 is 65 moved to the edge of the pit C, on the rails 2, it is arrested in its further progress by the bumper 3, and the chair is locked automatically to the bumper 3, by means of the 70 gravitation catch 5, which is pivoted on the chair, as shown in Fig. 2. This figure also shows the bumper 4, on the outer end of the rail to prevent the chair from getting off the rail. Figure 2, also shows a shoe resting on the shoe-rest 6, and 12 represents the relative position of the eye of the operator while 75 polishing the shoe 7 which is below the curtain 10, and which protects the skirt 8 from any polish or débris. The hand-rail 9 enables the customer to pull the chair to the 80 pit or to shove it from the pit as desired. The floor 14, of the store projects over the outer edge of the floor 15 of the pit so as to 85 cover shelving or appliances used by the operator as shown in Figs. 2, 5, and 6. The 85 pit floor 15 is built about thirty inches below the store floor 14 so as to allow the operator convenient access to the shoe while in a standing position and operating the rotary brush 24, as shown mounted on the flexible 90 shaft 23 in Fig. 3.

In Fig. 4, is shown, in the sectional elevation, a tubular standard 16 upon which the rotatable motor suspension members are pivotally supported. In Fig. 4, the motor 20 95 is shown suspended on the horizontal arm 18, which is rigidly secured by means of the rotatable suspension head 17, to the rotating sleeve member 29. The motor 20 is shown slidably connected by means of the hangers 100 19, which may be any desired form to suit, to the horizontal arm 18, which arm is secured by threaded connection to said head 17. The head 17, may be supplied with a multiplicity of arms 18, as shown in Fig. 1, 105 as provided for several operators to work in the same large pit at the same time on several sets of shoes. 22, 22, represent insu-

lated spring contacts provided to connect the circuit of the leads 21, 21, supplying the electric current to the motor 20, and providing means for the continuance of the current while the head 17, is allowed to revolve on the pivot of the standard 16.

When but one operator is provided for I use the form of pit and of motor-hanger shown in Figs. 5, and 6. This shows the 10 motor 20, suspended under the edge of the floor 14, on a horizontal rod 28, serving as a track for the roller-carried carrier 27.

As shown in Fig. 2, the lower edge 11 of the curtain 10 is supposed to be high enough 15 to allow the operation of the use of the brush 24.

Having thus described my invention, I claim as follows:

1. The combination with an enclosing 20 structure, of a shoe-dressing apparatus, comprising a pit below the level of the floor of said structure, and provided to be occupied by the operator, a protecting railing about said pit above the floor, tracks on said floor 25 and approaching to the edge of said pit, chairs movably mounted on said tracks and locking means provided to secure said chairs near the edge of the pit.

2. In a shoe-dressing apparatus of the 30 class described, the combination of a platform formed by the floor in a room, a pit in said floor for the accommodation of the operator of the apparatus, flanged rails approaching the edge of said pit for the carrying of the customers whose shoes are to be dressed, a plurality of wheeled chairs on said rails, means for locking said chairs securely at the edge of said pit, a protecting railing about the edge of the pit, and a

curtain on said railing, for the purposes 40 specified.

3. In a shoe-dressing apparatus of the class described, the combination with an enclosing structure having a floor of a pit below the level of the floor of said structure, 45 to be occupied by the operator, a protecting railing about the edge of said pit and above said floor, a curtain pendant from said rail, metal tracks on said floor diverging from the edge of said pit, and wheel-mounted 50 chairs on said tracks for the service of the patrons.

4. A shoe-dressing apparatus of the class described, comprising with an enclosing structure having a floor, a pit below the 55 level of said floor for the accommodation of the operator, a protecting railing about the edge of said pit and above the said floor, a pendant curtain reaching from said railing to near said floor, and chairs removably 60 situated on said floor near the edge of said pit for the accommodation of the patrons.

5. A shoe-dressing apparatus comprising with an enclosing structure having a floor, a convenient pit below the plane of the floor, 65 a protecting railing about the edge of said pit and extending above the said floor, a pendant curtain extending from said railing to near said floor, metal tracks on said floor 70 extending away from the edge of said pit, chairs mounted on said tracks, in combination with foot rests in rigid position near the edge of said pit.

JAMES E. KIPFER.
